UNITED STATES PATENT OFFICE.

WILLIAM E. BORST, OF GRAND RAPIDS, MICHIGAN, ASSIGNOR OF ONE-HALF TO CLARENCE C. GILLEO, OF GRAND RAPIDS, MICHIGAN.

MORTISE-MOLE

1,353,888.

Specification of Letters Patent. Patented Sept. 28, 1920.

Application filed October 28, 1918. Serial No. 259,764.

To all whom it may concern:

Be it known that I, WILLIAM E. BORST, a citizen of the United States of America, residing at Grand Rapids, in the county of Kent and State of Michigan, have invented certain new and useful Improvements in Mortise-Molds; and I do hereby declare the following to be a full, clear, and exact description of the invention, such as will enable others skilled in the art to which it appertains to make and use the same.

This invention relates to a mortise mold adapted to be applied to the mold wheel of a linotype casting machine for the production of an open casting of type metal in which a regular type slug cast by the usual molds of linotype machines may be inserted, the open casting or mortise at one edge being also formed with a raised border such that the mortise with the slug therein when placed in a form and used in printing will produce what is known as a "box heading" several of which are ordinarily used in each issue of a newspaper. Heretofore it has been the usual practice to set up the box heading by means of suitable characters and spacers, the operation taking considerable time. With my invention, the open mortises made with the mold of my invention may be cast rapidly and the slugs containing the cast heading to go within the mortise are readily and rapidly cast in the usual manner, whereby the production of box headings may be greatly facilitated. It is the object and purpose of this invention to produce a mold which will produce the mortises for receiving the type slugs, said mold being applicable to mold wheels of linotype machines, and with which box heading mortises may be cast with great rapidity.

To this end I have made the construction illustrated in the accompanying drawings, in which,

Figure 1 is a front elevation of the mold.

Fig. 2 is a lower plan view thereof.

Fig. 3 is a view substantially on the line 3—3 of Fig. 1 looking in the direction indicated by the arrows at 3, 3.

Fig. 4 is a view of the mortise mold bar forming an element of the mold looking substantially in the direction of the arrows 4, 4 of Fig. 1.

Fig. 5 is a view looking in the direction of the arrows 5, 5 of Fig. 1.

Fig. 6 is a front elevation of the casting 55 or mortise produced by the mold.

Fig. 7 is an under plan thereof.

Fig. 8 is an end view.

Fig. 9 a transverse section therethrough.

Fig. 10 is a rear view of the mortise. 60

Fig. 11 is a front view of a mortise with a type slug fitted therein.

Fig. 12 is an end elevation of the mold, and

Figs. 13 and 14 are, respectively, an elevation and end view of the type slug adapted to fit in the mortise produced by this mold. 65

Fig. 15 is a front elevation of the grooved matrix which comes in front of the mold 70 during the operation of casting the box; and

Fig. 16 is an end elevation thereof.

Like reference characters refer to like parts in the different views of the drawings.

In the construction of the mold an upper 75 member 1 is provided which has a smooth under face 2, said member being known as the mold proper. At each end of the mold spacers 3 and 4 are located, the same being readily detachable from the mold and capable of replacement by spacer members of different lengths for different lengths of castings. At each end of the mold fingers 5 project, being adapted to enter slots 6 in the ends of the mold cap 7 for releasably 80 holding the mold and cap together. This cap has an upper surface 8 on which a plurality of tapered grooves 9 are cut for helping the withdrawal of the casting from the mold. These members of the mold, the mold proper and the cap therefor are not new, being used in the linotype machine for the production of type slugs, the face 8 being spaced from the face 2 by suitable spacers such as 3 and 4 and the metal forced into the mold 90 from behind and against the matrices in the mold face of the linotype machine for producing type slugs, as is well understood by all familiar with linotype casting machines. 95

In my invention two spacers 10 of the same length as the spacers 3 and 4 are located at the ends of the cap 7 against the face 8, and against such spacers a bar 11 is placed, the same extending the full length of the mold and having deep slots 12 cut from the front edge of the bar, leaving only a relatively narrow connecting neck 13 at the bottom of each slot. Slots 12 are located so

that when the cap is attached to the mold the inner ends of spacers 3, 4 and 10 lie in alignment with those parts of the bar 11 forming the outer sides of said slots. The 5 bar 11 with the interposed spacers 10 are secured to the cap by screws 14. In this manner there is made a mold having a central core 11* between the slots 12 and located between open spaces 15 and 16 which spaces 10 communicate with the slots 12 so that on introduction of molten type metal into the mold an open casting is made where the metal has filled spaces 15, 16 and slots 12.

The metal is forced into the mold from 15 behind entering the spaces 15 and 16 and flowing around the necks 13 to fill the slots 12. The casting or mortise made includes sides 17 and 18 and ends 19, the side 18 having a plurality of tapering ribs 21 thereon 20 as shown from metal entering the grooves 9. The ends 19 have recesses 20 where the necks 13 are located, and an open space 22 is made in which the type slug carrying the type 25 characters of the title for the box heading may be positioned. The mold face of the linotype machine is equipped with a matrix 25 having a groove 26 which when the metal is forced into it makes a raised border 23 on the front edges of the sides and ends of 30 the mortise casting made and which lies in the same plane with the faces of the type characters so that when ink is applied and the same impressed on paper a heading having a continuous inclosing border is made. 35 The type slug 24 is of the usual character cast in linotype machines, and the thickness of the bar 11 is such that the opening 22 made by casting around the core 11* is just sufficient to receive the slug.

40 With a mold made in accordance with my invention, the formation of box heading mortises is very expeditious, it being possible to form them at the rate of three or four a minute, each being perfect in every 45 respect and in which any desired heading may be placed. By changing the length of the core portion 11*, that is by differently locating the slots 12 in the bar 11, and using corresponding lengths of spacers 3, 4 and 50 10, box heading mortises may be made of different lengths as desired, and the thickness of the bar 11 of course is controlling as to the size of type slug which may be located in the mortise, which thickness of bar 55 may be readily changed without changing the operation of the mold. In practice, it is advisable to cast a large number of mortises

at one time, all that will be likely to be used for a week or so ahead, this being done at some time when work on a linotype casting 60 machine is slack and in this manner a considerable saving of time is accomplished as has been proven by actual practice of the invention.

I claim:

1. In a construction of the character described, a mold and cap therefor, and a bar disposed between the mold and cap and spaced from the sides of the mold and cap at its central portion, said bar having relatively deep slots cut in its front edge adjacent the ends of the mold and cap whereby molten type metal may be forced into the spaces between the bar and the mold and cap and thence into the slots in the bar to 75 form a mortise of type metal having a central opening therethrough adapted to receive a cast metal type slug.

2. A mold adapted to be applied to the mold wheel of a linotype casting machine 80 comprising a mold and cap, and a core of rectangular form located between the mold and cap and connected thereto, said core having a width equal to the thickness of the mold whereby molten metal may be forced 85 into the mold around the core to form an open cast box adapted to receive a cast metal type slug, substantially as described.

3. A mold comprising means adapted to be connected to the mold wheel of a linotype casting machine and including a core 90 connected to said means around which molten type metal may be forced to form an open box in which cast metal linotype slugs may be inserted, substantially as described.

4. Means for casting an open box of type metal, and means for forming a raised border on the edges of the box around the opening therein, substantially as described.

5. A linotype mold comprising a mold 100 and cap therefor, a core secured between and spaced from the adjacent sides of the mold and cap whereby molten type metal may be forced into the mold from the rear and flow around the core, and a matrix adapted 105 to be positioned in front of the mold and provided with a recess to receive molten metal whereby a raised border is formed on the casting made in the mold at the front thereof and around the core, substantially as 110 described.

In testimony whereof I affix my signature

WILLIAM E. BORST.
